UNITED STATES PATENT OFFICE.

VICTOR LAUER, OF LITTLE BERGER, MISSOURI.

HARNESS-HOOK.

SPECIFICATION forming part of Letters Patent No. 613,579, dated November 1, 1898.

Application filed August 30, 1897. Serial No. 649,997. (No model.)

To all whom it may concern:

Be it known that I, VICTOR LAUER, a citizen of the United States, residing at Little Berger, in the county of Gasconade and State 5 of Missouri, have invented certain new and useful Improvements in Harness-Hooks; and I do hereby declare the following to be a full, clear, and exact description of the invention, such as will enable others skilled in the art to 10 which it appertains to make and use the same.

This invention relates to a novel harness-hook, the object being to produce an extremely simple and highly efficient hook consisting of but two parts and requiring no 15 springs or other loose or fragile elements likely to become deranged in use.

To the accomplishment of this object the invention consists in constructing a harness-hook composed of an elongated metal loop 20 and a curved tongue of peculiar construction carried by the loop and having a hooked end engaging the extremity of the loop to retain the device in the closed position.

Referring to the drawings, Figure 1 is a 25 perspective view of my improved hook applied to the end of a strap, showing the tongue in the closed position; and Fig. 2 is a similar view showing the tongue in the open position.

Referring to the numerals on the drawings, 30 1 indicates an elongated metal hook loop or body having a downwardly-bent end 2 and provided at its opposite extremity with a preferably integral transverse strap-loop 3, by means of which the device may be secured 35 to the strap or other part.

4 indicates a curved substantially semicircular tongue of somewhat larger diameter than the diameter of the opening through the loop 1 and provided at one end with a comparatively small neck 5, extending through 40 the loop and terminating in an enlarged head 6, which is formed upon the tongue after the latter has been passed through the loop, and the tongue is then incapable of removal from

45 the loop. The opposite end of the tongue is provided with a comparatively narrow hook 7, designed to pass through the loop and to engage the extremity 2 thereof. It will thus be seen that while the neck 5 is of sufficient 50 length to permit the hook end of the tongue to be passed freely through the loop for the purpose of opening and closing the device

the tongue is incapable of detachment and when once connected or hooked to the loop will constitute an efficient hook, the security 55 of which will be increased as the strain is greater.

While I have illustrated and described my device as a hook for harness, it is obvious that it might be used in various other connections—as, for instance, as an equivalent of the cockeye and singletree-hook or of an ordinary line-buckle, &c.—and while the present embodiment of my invention appears at this time to be preferable I do not desire to 65 limit myself to the structural details set out, but reserve the right to change, modify, or vary such details at will within the scope of my invention.

Having thus described my invention, what 70 I claim as new, and desire to secure by Letters Patent, is—

1. A harness-hook comprising a body having an elongated opening therein, and a bent tongue whose ends extend through said opening and are provided with means for engaging the body.

2. A harness-hook comprising a body having an elongated opening therein, and a bent tongue whose ends extend through said opening from the same side, and are provided with means for engaging the body.

3. A harness-hook comprising a body having an elongated opening therein, and a bent tongue whose ends extend through said opening from the same side of the body, one of which ends is provided with a head, and the other with a hook.

4. The combination with a loop, of a bent tongue whose ends extend through said loop from the same side, one of which is provided with a head or shoulder wider than the opening through said loop, and the other is provided with a hook narrower than the opening through said loop, but adapted to engage the end thereof.

5. The combination with a loop, of a bent tongue whose ends extend through said loop from the same side, both of which are provided with engaging means, and the tongue being provided at a point intermediate of its ends with a projection wider than the opening through said loop.

6. In a device of the character described,

the combination with an elongated loop, of a substantially semicircular tongue provided with a reduced neck extending through the loop and with a terminal head, and a comparatively narrow hook upon the opposite extremity of the tongue and designed to engage one end of the loop, substantially as specified.

In testimony whereof I have signed this specification in the presence of two subscribing witnesses.

VICTOR LAUER.
